UNITED STATES PATENT OFFICE.

ORRELL ASHTON, OF SWAMPSOFT, MASSACHUSETTS, ASSIGNOR TO UNITED SHOE MACHINERY COMPANY, OF PATERSON, NEW JERSEY, A CORPORATION OF NEW JERSEY.

MACHINE FOR USE IN THE MANUFACTURE OF BOOTS AND SHOES.

1,137,564.

Specification of Letters Patent. Patented Apr. 27, 1915.

Application filed November 10, 1909. Serial No. 527,210.

To all whom it may concern:

Be it known that I, ORRELL ASHTON, a citizen of the United States, residing at Swampscott, in the county of Essex and State of Massachusetts, have invented certain Improvements in Machines for Use in the Manufacture of Boots and Shoes, of which the following description, in connection with the accompanying drawings, is a specification, like reference characters on the drawings indicating like parts in the several figures.

This invention relates to machines for use in working an upper over a last and is illustrated and will be explained as incorporated in a pulling-over and lasting machine having the general organization set forth in prior application for Letters Patent of the United States, Ser. No. 375,669, filed May 25, 1907 by R. F. McFeely. That machine comprises means for pulling-over an upper and means for automatically lasting the toe portion of the upper.

One important feature of this invention consists in provisions for adjustment of the toe lasting means to the shoe after the upper pulling operation and prior to the automatic operation of the lasting means. It has been found in practice that there is sufficient variation in the conditions presented by different shoes, as for instance in the plane of the shoe bottom, to make possible improved results if the toe lasting means can be manually positioned around the toe at the correct elevation prior to their power driven lasting movement. This is perhaps of special importance in turn shoe work, upon which this machine is at present chiefly used, because a turn shoe sole is soft and in temper when the shoe is lasted and its edge projects outwardly beyond the edge of the last bottom. For obtaining the improved results referred to I have mounted the toe lasting means for movement on its carrier toward and from the shoe, and also preferably vertically to a limited extent. The lasting means is normally latched to its carrier so that it is retracted thereby from the shoe at the end of the pulling-over and lasting operations and held out of the way during the next pulling-over operation. When the shoe has been made ready for the toe lasting the latch is released and a spring forces the lasting means into toe embracing relation to

the shoe. The operator then can adjust the lasting devices into desired relation to the plane of the bottom of the shoe that is in the machine and can make any other adaptation needed for the particular conditions presented so that when the power mechanism is started the upper will be properly gathered and overwiped into lasted position and, as herein shown, will be fastened by lasting tacks. The latch is caused to reengage the lasting means during the power operation and cause said means to be automatically retracted to its initial position after the fastenings have been inserted. For the convenience of the operator this position is sufficiently remote from the shoe to allow unobstructed inspection of and access to the shoe during its preparation for lasting and this remoteness of initial position is a factor in the importance of this feature of the invention by which accurate relation of the lasting means to the shoe can be assured before the power is applied to said means.

Another feature of this invention consists in the provision of upper clamping means to assist in holding the upper for the action of the lasting means. It is found that under some conditions improved results are obtained from the lasting means if the upper can be held to the side face of the shoe below the wipers during the operation of said wipers. Preferably the clamping means, herein shown as thin plates or jaws, will be mounted to engage the upper while it is held stretched by the pulling-over means and to clamp the upper against the edge of the shoe sole. When so arranged the clamping jaws constitute guides over which the lasting means slide to gather the upper and lay it into lasted position upon the shoe bottom. As I am advised it is new by this invention to provide a machine having power operated lasting means with upper holding or clamping jaws which can be manually positioned before the automatic actuation of the lasting means. These jaws can be held pressed against the shoe, as by the hand of the operator, while the toe grippers are disengaged from the upper and retired from the path of the lasting means prior to the power actuation of the lasting means. The clamping jaws are not necessary under all conditions and I have obtained good results by the use of the lasting means to embrace

the upper at the upper edge of the sole and clamp it against the sole margin while releasing the toe grippers as just described. It may be well here to explain that in the lasting of turn shoes I do not desire to obtain that conformation of the margin of the upper to the contour of the underlying face of the feather and shoulder of the sole which is sought and obtained in welt shoe lasting by wiping hard over the feather and firmly against the shoulder and is then usually perfected by compression. I find that in turn shoe work, in which the upper is sewed to the sole with lining side out and is thereafter turned to present the finished side of the leather out, the best appearing shoe after it is turned is produced if the upper is gathered over the toe of the sole and fastened at a few points, without pressure or definite creasing. The fullness around the toe is most evenly and smoothly distributed by the sewing operation without producing wrinkles in the turned shoe if the shoe is thus prepared for the sewing machine, rather than being prepared as is a welt shoe which is to be sewed right side out.

I have discovered that improved lasting of the toe of the shoe can be obtained by the use of pulling-over grippers which are formed in sections and arranged to engage a continuous section of upper extending from one side of the shoe around the toe to the other side. The action of such grippers in preparing and, it may be holding, the upper for the operation of the lasting means produces a smoother and more evenly lasted toe than can be otherwise obtained so far as I am advised. Advantageously the toe grippers may be mounted to permit movement in the direction of the edge of the last, as for example rotative movement, to adjust the upper edgewise around the toe of the last. The portion of the invention which relates strictly to the grippers is made the subject-matter of application Ser. No. 568,918 filed June 25, 1910, which is a continuation of this application as to subject matter which is common to both cases.

Another feature of the invention which is of particular importance in turn shoe work consists in gripper positioning and actuating mechanism arranged to cause the grippers to stretch the upper about the last out of contact with the side faces of the last, and therefore out of contact with the overhanging edge of the forward portion of the sole, and then to wrap the upper inwardly over the edge of the sole. This inward wrapping is or may be made to take place during the latter part of the stretching movement and before the lasting begins.

A further feature of this invention is found in an organization of an upper pulling and fastening machine by which the upper fastening mechanism is caused, dur-

ing the insertion of the tacks, to aid in forcing the upper in the direction of the over-drawing movement. This result is obtained by providing a tack holder which is mounted to be moved forwardly by the tack drivers and has a driver passage with which the driver forms an angle such that the holder is moved in the direction of the overdrawing movement upon the upper during the descent of the driver to insert a fastening tack. This is of particular advantage where, as in turn shoe work, the upper is not molded hard down upon the surface of the sole before being fastened and can therefore be drawn farther over the sole by such action of the tacking mechanism. The portion of this invention which relates strictly to the tacking mechanism is not herein claimed but is made the subject-matter of application Ser. No. 591,622, filed Nov. 10, 1910, as a continuation of this application in so far as the two applications disclose the same subject-matter.

A further feature is found in the provision for independent adjustment of the side grippers, located at opposite sides of the shoe, inwardly and outwardly. This is embodied in a device for separately shifting the side gripper spreading levers by which the side grippers are moved outwardly by power against the resistance of overdraw springs.

Another feature of this invention is found in means for depressing the last manually into the pulled upper. This is shown as embodied in means arranged for manual operation while the upper is under strain. As herein shown the heel end of the last is rocked downwardly relatively to the forward portion which may pivot on the toe end of the sole rest. This rocking movement has the effect of producing a differential strain on the upper held by different portions of the gripping means and it may be used to advantage to draw the upper down into the hollow over the thin ball that is found in some lasts, particularly those which have high toes.

The foregoing and other features of this invention, including certain important details of construction and combinations of parts, will be more fully explained in the following description taken with the accompanying drawings of a machine embodying the invention and will then be pointed out in the claims.

Figure 1 is a side elevation of a machine embodying this invention; Fig. 2 is a perspective view of a sample product of the machine; Fig. 3 is a side elevation of the upper pulling and the last resting and depressing means; Fig. 4 is a perspective view of the toe grippers; Fig. 5 shows one pair of the sectional jaws; Fig. 6 is a bottom view of the toe grippers; Fig. 7 is a perspective

view of the side grippers showing the gripper positioning mechanism also; Fig. 8 is a plan of the positioning mechanism; Fig. 9 is a detail thereof; Fig. 10 is a side elevation showing in full and dotted lines inoperative and initial operative positions of the toe lasting mechanism, together with the grippers which are holding the upper in pulled over position for the lasting to be commenced. Fig. 11 is a plan with the lasting devices in the dotted line relation of Fig. 10; Fig. 12 shows the upper over-worked to lasted position and one tacker in operative position; Fig. 13 is a detail of the lasting devices.

The machine in its general organization resembles that shown in United States Letters Patent No. 663,777, granted December 11, 1900, on application of Ronald F. McFeely and in the development of that machine which is fully illustrated and described in McFeely's pending application Serial No. 375,669. A detailed description of the well known portions of this machine is not required herein but an understanding thereof may be had from said prior specifications.

The head of the machine is carried on a pedestal at such a height that the operator may look obliquely upwardly at the shoe being operated upon and that he may have the several levers and other manually operated devices within convenient reach. The head supports a shoe bottom rest 4, against which the shoe is positioned with its bottom and the edges of the upper faced obliquely upwardly and the head contains a cam shaft 5 from which are driven cams that operate the several power operated mechanisms of the machine. The cams 6 and 7 at the rear of the shaft operate respectively the two side grippers 8, 9 and the toe grippers 10 through yielding connections 11, 12 with the updraw levers 14, 15 from near the front ends of which the grippers are suspended by joints permitting freedom of movement to the grippers. The levers are extended forwardly to provide handles by which the operator can manipulate the grippers to increase or diminish the stretching of the upper or to shift the upper. Relative vertical movement of the side grippers pulls the upper transversely of the last one way or (and) the other, thus tending to strain the upper farther, and such movement may be made to position the upper transversely of the last, to work it down into the hollow over the ball of the last, and to stretch or draw the upper into conformity to the contour of the particular last that is in the machine. This drafting of the upper which is effected by the power and manual movements of the side grippers, and the movements of the toe grippers, which will be described, is a very important characteristic of

the pulling over operation whether effected by hand workmen or by the machines of the type herein shown. This preliminary operation, preparatory to lasting, has for its object the positioning and adjustment of the upper and its associated materials and parts upon the last to give a correctly-built appearance to the shoe, and the further object of distributing the upper stock according to the formantion of the particular last and of establishing the initial lines of strain which will assist in causing the upper to maintain the form of the last after the last has been withdrawn. This pulling over operation in which the upper, in addition to being correctly positioned on the last, is pulled at a few selected points and drafted to the last, makes the shoe ready for the detail lasting to be described in which continuous sections of the prepared upper are worked into final position to be fastened and it gives to the finished shoe that permanent shape and well built appearance which characterizes high grade shoes of the present time.

The toe gripper lever 15 has, in addition to its handle, a lever 16 connected by a slide 17 with the jaw closing mechanism to enable the operator conveniently to open the jaws of the toe gripper independently of the regular operation of the machine. The toe gripper bar 10 is made cylindrical at its lower end and on it is rotatably mounted a block 22 having a chamber for a spring 24 and recesses for two rotatable stems 25 on each of which is formed a fixed gripper jaw 26. The movable gripper jaw 28 is pivoted to the outer side of the fixed jaw at 29 and has an eye to embrace the stem 25. The inner side of the eye interlocks with a notched depending extension of a sleeve 30. The sleeves 30 have notches in their adjacent sides into which fits a disk or plate 32 having a central oblong slot to receive the T-head 33 of the bar 10 and safely interlock therewith when the bar and block 22 are relatively rotated to their normal position. Pins 21 carried on a spring plate 23 extend through the walls of the block 22 into annular grooves in the heads of the stems 25. This connection of the stems with the block 22 and the connection of the sleeves 30 with the bar 10 permits free turning movement of one pair of gripper jaws or gripper section relatively to the other pair or section, so that the two sections can freely conform to the width and shape of the toe portion of the last over which the upper is being pulled. The block 22 is also rotatable upon the bar 10, preferably through a limited angle, so that the gripper sections cannot only adjust themselves about the axes of their respective stems, but they can move together about the axis of the bar 10. By these arrangements for turning movements,

each gripper section can be displaced, within limits, both longitudinally and transversely of the shoe for adaptation to the shape and position of the last and also for effecting adjustment of the upper upon the last. This latter use is provided for by applying a hand bar 35 to the block 22.

The side grippers 8 and 9, which may be of known construction, are suspended by ball joints from their levers 14 and are guided with the narrow body portion of their blocks 40 within relatively wide ways in the head so that they are free to move with the upper when the upper is adjusted around the toe by the rotation of the toe gripper block 22. This adjustment of the upper by means of the toe gripper, with the side grippers free to move with the upper is found very satisfactory for tip line positioning. Tip line positioning may involve adjustment of the tip line or seam angularly with relation to the median line of the last and this is effected by the angular movement of the toe gripper by the hand bar 35 as described. Tip positioning also involves adjustment longitudinally of the shoe for obtaining correct and uniform length of tips. This is obtained in the present machine by manually increasing or diminishing the pull of the toe gripper by the use of the handle on lever 15. By reason of the fact that the illustrated curved toe grippers engage the upper at the sides, as well as at the end of the toe, they do not tend to bow the tip seam and as the side grippers move freely lengthwise of the last they offer no retardation tending to cause the tip seam to be bowed when the upper is pulled upon by the toe gripper. Very effective stretching of the upper lengthwise of the last, and conformation of the upper to the contour of the heel portion and side faces of the last, is obtained in this machine by the use of the wide curved grippers having engagement with the entire toe portion of the upper at the sides and end so that a lengthwise pulling is effected throughout the breadth of the upper. This thoroughly tensions the vamp and quarter seam along the sides of the last, as well as the side margins of the vamp, without excessively straining the vamp along its median line and at the throat. This result is appreciated in making low cut shoes, the upper edges of which should snugly hug the last and the wearer's feet in order to retain their shape and be comfortable. The freedom of movement of the side grippers of course contributes to this successful use of the toe gripper. The side grippers have on their front and rear faces of their blocks 40 opposed inclines 42 which seat in corresponding inclines in the head when the grippers are restored to shoe receiving position.

These inclines reguide the side grippers always to a normal gripping position longitudinally of the shoe, no matter to what position they may have been displaced during the operation on the last shoe.

The bar 35, together with the plate 23, is fastened by a single screw 36. Either with or without loosening the screw, the plate and the hand bar may be turned to uncover the pins 21 and permit them to be taken out of the stems 25 and, when the block 22 is turned 90° on the bar 10, the two stems and the gripper jaws can be removed. This provision for readily removing one set of jaws and substituting another enables the machine to be easily provided at all times with grippers having jaws suitable for the work that is in hand, even though the sizes may vary from children's to women's, for example. The plate 23 applies sufficient friction through the pins to the stems 25 to prevent them from undesirable loose movement. It will be noted that the jaws 26 and 28 are so formed and arranged that their gripping faces are at a small angle to the plane of the last bottom by reason of which they are adapted to receive the upper of the forward portion of the shoe in its normal, outwardly flared position. This enables initial folds or puckers in the upper to be avoided and permits the upper to be stretched smoothly over the entire end portion of the last and produce a smooth edged toe, as shown in Fig. 2. The toe and side grippers may, if desired, be connected as shown in Fig. 3, by cylindrical pins 43, 44 arranged to move endwise and turn freely in guideways on the side and front pincers, respectively, and connected together by transverse pins, as shown in dotted lines, to permit relative angular movement of the toe and side grippers.

The lateral position or spread of the grippers for seizing the upper is determined and effected after each operation by the spreading mechanism, shown in Figs. 7 and 8, which is in general the same as that described in the McFeely specifications, with the addition of means for independently adjusting each of the side grippers. The grippers are pressed inwardly by springs 45 and the side grippers are reversely moved by levers 46 having contact blocks engaging the inner sides of the gripper bars 8 and 9 and have rolls 47 to engage endwise movable wedges 48, as shown in said prior machines. The fulcrums or stationary supports for the levers are formed by eccentric portions 50 of pins 52 which are rotatable in their supports, as by the use of a pin 53, and are locked by a set screw 54. By adjustment of the eccentrics 50, the levers 46 may be moved angularly about the axes of rolls 47 to throw their forward ends and the gripper bars 8 and 9 outwardly or inwardly.

This adjustment also shifts the gripper bars by the fact that it moves the levers longitudinally of the wedges 48.

The bottom rest 4 forms an abutment for 5 the last to hold it against the pull of the grippers and the rest has numerous automatically effected movements, some of which can be supplemented by hand power, as is well understood by those familiar with the 10 machine, but which are not necessary to detail in connection with this invention. In addition to the bottom rest, the machine is herein provided, see Fig. 3, with a last depressor 41 arranged to engage the sole of 15 the last over the instep and fulcrumed in the rest carrier and having a toothed engagement with a pinion 431. This pinion has detachable engagement with the automatically driven lever 152 of the sole rest operating mechanism of the known machine and the pinion is connected by its shaft with the hand lever 160 at the side of the machine, see Fig. 1, which has the disconnector 166 for disengaging the pawl or swinging arm 20 156 of lever 152 as is well understood when it is desired to actuate the depressor by hand lever 160. This depressor can serve to move the rear part of the last downwardly with 25 relation to the toe end and, by this movement relatively to the grippers, to effect a differential stretching of the upper for drawing the upper into the hollow portion of the last over the ball. The last is lightly 30 rested at the heel to resist rearward displacement in the heel rest 2 which permits the heel end of the last to move up and down relatively to the toe end with small resistance when the depressor is operated. The depressor can be operated manually instead 35 of the side grippers to draw the upper more tightly and offers the advantage that it can be moved with one hand while the two side grippers require both hands.

The means which coöperate with the pulling-over grippers to work the upper over the last bottom into lasted position about the forward portion of the shoe and to secure it in overworked condition is carried by an arm 60 which is suspended from the upper portion 40 of the head and swings inwardly from the position shown in Fig. 1. This lasting mechanism comprises two sets of devices. The first set includes those devices 70 which are shown in holding engagement with the upper in Fig. 11 and which will be called 45 clamps for the purpose of designation.

The clamps are carried by a plate 62 which also carries the lasting plates 80 which constitute the other set of devices and 50 are located immediately above the clamps 70, Fig. 10, to be guided, as to the plane of their operative movement, in sliding contact therewith. The plate 62 is yieldingly upheld by a spring 65 encircling a bolt which

depends from the toe tack block 92, carried 55 on the lower end of the arm 60, the spring being confined under adjustable tension by a nut and permitting limiting tilting movement of the plate 62 whereby the lasting devices may be adjusted vertically relatively to the 60 plane of the shoe bottom. In practice the operator tilts the plate up angularly so as to bring the jaws 70 where they will embrace the shoe around the edge of the sole and then the 65 wipers guided thereover will close with a rubbing action over the margin of the shoe bottom to lay the upper over the feather of a turn shoe sole and against the shoulder thereof. The plate 62 is slotted lengthwise as best shown in Fig. 12 so that it can slide 70 lengthwise of the shoe relative to the tack block 92 from the position Fig. 10 to that Fig. 11. This movement of the lasting devices relatively to the shoe angularly and lengthwise from a position remote from 75 the shoe where the shoe is freely observable to the workman to a position in proper relation to the shoe for the power operated movements to be imparted to it for properly lasting the shoe toe has proven to be of great 80 practical importance in the reorganization and development, respectively, of the machines described in the McFeely patent and application above mentioned to produce the 85 machine of the present invention. The plate 90 62 and the lasting devices are retained normally in retracted position away from the shoe by a latch 67 fixed on the tack block and engaging in the outer end of the slot in plate 62 as in Fig. 10. This can be readily 95 released by the operator when he is ready to position the lasting devices, whereupon a spring 66 encircling a guide rod 64 and acting against a forked lug 63 on plate 62 moves the plate and the lasting devices forwardly to or toward the position of the latter shown by dotted lines in Fig. 10 and shown by full lines in Fig. 11.

The clamping jaws 70 are shaped to embrace the toe and grip the upper against the edge of the sole. Their adjacent ends are pivoted together and each jaw has a pin and slot connection, Fig. 11, at the outer side of the pivot to the head of a sliding stem 73 which is movable outwardly and away from 110 the center plane of the machine in an oblique guideway formed for it in the enlarged head of plate 62. This head has also a sleeve 115 74 guided in a parallel way in the plate, and a spring 75 permits the jaw holder to yield 120 away from the shoe. Each of the sleeves 74 contains a spring-pressed plunger 76 and these mountings normally hold the jaws 70 in the relative positions shown in Fig. 13. The plate 62 carries a block the depending portion 82 of which constitutes means through 125 which the operator can press the jaws 70 against the pulled upper and cause them to

move relatively from the positions shown in Fig. 13 to the stock clamping positions conformable to the contour of the toe shown in Fig. 11. The pin and slot connections at 72, 72, as well as the other described jointing and supporting connections, contribute to the capacity of the jaws to adapt themselves to different narrow and wide and right and left shapes of toes and to clamp the upper smoothly and so securely that the toe grippers can be released. Before the toe grippers are released the jaws may be used, if desired, to wipe the upper smoothly up the side faces of the toe so as to present it in desired condition for lasting over the shoe bottom. The loose connection permitting horizontal endwise and limited vertical tipping movement of the plate 62 relatively to the tack block 92 allows the operator to effect these movements of the jaws by force transmitted through the finger piece 82. Operators usually maintain pressure of the jaws 70 until the wipers are operated by keeping a finger upon the abutment 82. In practice I have found it to be satisfactory to open the toe grippers manually by lifting the hand latch 16 which, through the connection 17, lifts the block 22 and jaw stems 25 to release the upper. It should be mentioned that the toe grippers are arranged to hold the upper a little away from the side faces of the last at the beginning of the updraw so as not to lift the edge of the innersole, or the sole which in turn shoes projects beyond the side of the last. This is effected by the cam or incline 55 which is formed on the inner side of bar 10 and is engaged by the end of the spreading bar 51 to control and change the outward position of the toe grippers during the updraw. This illustrated arrangement provides for moving the toe grippers inwardly to wrap about the last the upper which has been initially pulled while it was out of touch with the edge of the sole. The jaw sections may turn to conform to the smaller curve as the grippers move inwardly and the grippers preferably come to rest in about that relation to the edge of the shoe which appears in Fig. 11, that is, with the upper slightly overdrawn and hugging the edge of the last or sole so that the clamping devices 70 can clamp the upper securely.

The lasting plates 80, 80 lie in a plane immediately over the jaws 70 and are separately pivoted to the plate 62 at 86, 86 and when the plate 62 is advanced from Fig. 13 to Fig. 11 position the ends of the plates 80 so connected are advanced. The outer ends of the plates 80 are, however, connected by rolls 90 standing in cam slots 88, Figs. 10 and 11, with the tack block 92. It is therefore only when the tack block is advanced by the power mechanism after the next treadling of the machine that the lasting plates are caused to act upon the shoe. In

this advance, which will be understood by comparing Fig. 11 with Fig. 12, the plates 80 are turned about their pivots 86 to sweep the upper over the corners of the toe from opposite sides simultaneously and in directions substantially perpendicular to the adjacent portions of the shoe edge. The pivots 86 tend to remain stationary during this swinging movement because of the engagement of jaws 70 with the shoe but as the tack block 92 advances along the longitudinal slot in plate 62 it ultimately comes to and strikes the end wall of the slot and thrusts the plate 62 ahead until abutment 82 engages hard enough against the end of the shoe. This engagement is a very substantial one, being the same that is relied upon to cause the tripping off of the toe tack drivers as fully explained in said prior Patent No. 663,777. During this movement of the tack block before the tack drivers descend the jaws 70 are forced by the power mechanism hard against the shoe, the springs 75 yielding to allow the plate 62 to advance; the corner wiper plates 80 are given a straight forward final movement; and the tack block 92 is advanced and acts as a middle or toe end wiper to lay the upper at the middle of the toe straight backwardly. The whole effect is to gather the stock into about the condition shown in Fig. 2 with a fold or plait at each side of the center of the toe tack *t* and a fold or plait, which is not of objectionable size, at the ends of the corner wipers just beyond the corner tacks *t'*. The three tacks *t* *t'* *t'* are inserted from the tack block 92 while the two side tacks at each side of the shoe are driven from the side tackers into stock which is pulled and then overwiped by the side grippers and the side wipers which latter may be like those described in said prior specifications. As the tack block advances relatively to the plate 62 and its rod 64 the spring 66 is compressed as in Fig. 12 until the latch 67 catches into the slot in the plate and locks the plate and its attached jaws and wipers to the tack block so that said parts are carried back with the tack block as shown in Fig. 10 where they will be out of the operator's way as he observes the pulling and effects adjustments of the next shoe.

The toe tack holder 97 or member containing the tack pockets is pivoted in the tack block 92 on a horizontal axis running transversely of the machine and so located that the tack holder hangs backwardly as in Fig. 1 but can be swung forwardly by the drivers as they descend into and through the pockets. For this purpose the tack pockets and driver passages are inclined and the driver block is pivoted to the driver bar at 98, as shown in Fig. 1, and held in normal position by a spring 99. As the drivers descend their ends enter the driver passages or tack pock-

ets in the block, the inclined walls of which cause the block and the drivers to be tilted forwardly and the tacks driven on a slant or inclination inwardly. The effect is like that 5 which would be obtained by mounting the driver bar to move in a path inclined downwardly and inwardly at an acute angle to the plane of the shoe bottom and the advantage of the illustrated arrangement is that 10 the necessity is avoided of building this machine to project far enough forwardly to allow the driver bar to be reciprocated at the described acute angle to the shoe bottom. There is also an advantage in that the tack 15 holder has given to it a forward, swinging movement by the drivers which causes it to force the stock inwardly from the edge of the last and, in making shoes over a channeled or shouldered innersole or sole, to jam 20 the upper materials up against the shoulder or channel lip at the moment of tacking.

In the use of the machine, an assembled shoe, comprising the last, innersole and upper materials, is presented to the machine in 25 the relation shown in Figs. 1 and 3. The marginal portion of the upper standing in its normal outwardly flared position at the toe end of the shoe is readily inserted into the jaws of the toe grippers which are 30 formed, as shown in Figs. 4 and 5, to receive the upper without necessarily bending or deflecting it from its normal position. The upper at the sides of the shoe normally stands in a substantially upright position 35 and readily finds its position between the jaws on the side grippers. The bottom rest determines the vertical position of the shoe in the machine and the toe grippers may form the means for positioning the shoe 40 lengthwise and the toe laterally. For this purpose the shoe may be presented with its toe end against and laterally centered in the curved toe grippers. This step of positioning the shoe with relation to the toe grippers has the added advantage that the 45 swinging sections of the grippers are automatically positioned relatively by engagement of the shoe therewith in accordance with the contour of the particular shoe 50 which is to be operated upon. The formation of the inner sides of the gripper sections to facilitate this relative positioning of shoe and toe grippers is well illustrated in Figs. 5 and 6. With the work thus presented, the machine is started and caused to 55 close and uplift the grippers for putting the upper under tension and then come to rest. The shoe now stands before the operator in a position inclined forwardly and upwardly 60 so that he can examine the upper and determine what, if any, re-adjustments, additional pulling, and drafting may be required for fitting the shoe properly to the contour of the particular last over which it is being 65 made. If the tip line does not bear the de-

sired angular relation to the length of the last, it is corrected or straightened by turning the grippers by means of the hand bar 35 on the toe grippers. The side grippers, by reason of the fact that they are free to move forwardly and backwardly, offer substantially no resistance to this tip straightening movement by the toe grippers for they can follow the adjacent edge of the upper in its forward and backward movement. If 70 the toe and side grippers are connected, as shown in Fig. 3, this following of the toe grippers by the side grippers is mechanically insured, and the tip straightening is accomplished by stretching the upper on one 75 side of the shoe between the rear end of the side gripper and the heel and relaxing it on the other side of the shoe. This has the advantage that the upper is not stretched lengthwise or distorted in any way between 80 the toe grippers and the side grippers in the tip straightening operation. Instead thereof, the entire forward portion of the upper from the rear end of one side gripper to the 85 rear end of the other is adjusted edgewise 90 around the last. This is the first time that this has been provided for in a pulling-over machine and my claims thereto are to be construed broadly. If the tip line is not in the right longitudinal position, or, as it is expressed, if the tip is not of the right length, the upper may be pulled farther forward by uplifting the toe gripper by means of the handle on its lever 15. While the side grippers are free to swing forwardly during this 95 forward straining of the upper by the toe gripper, the side grippers may advantageously be depressed to relax the tension on the upper during this forward straining. This can easily be done by the operator grasping 100 the two side levers with his two hands and pulling them downwardly while pressing upwardly with one or both thumbs upon the handle of the toe gripper lever. For this purpose the three gripper levers 14, 15, 14 105 are arranged close enough together to enable them to be readily engaged as described. If it is desired to adjust the upper transversely of the ball of the last, this is done by uplifting one side gripper and lowering the 110 other, and both side grippers may be uplifted for additionally stretching the upper 115 transversely of the last.

Some modern lasts are formed with a high or thick toe and a relatively low or thin ball 120 portion into which it is difficult to draw the upper in the pulling-over operation, particularly if the vamp of the upper has not been previously crimped. If this difficulty is met in any shoe, the last depressor 41 may be employed for tipping the last downwardly about the forward extremity of the toe rest as a fulcrum, thus putting additional tension on the upper over said low portion of the last. This tensioning of the upper by 125

the last depressor has the advantage, over 5 additionally tensioning by uplifting the side grippers, that the movement is an angular one causing gradually increasing tension from the high part of the toe backwardly to the low part of the ball and giving most effective distribution of the tension. The last depressor may be operated automatically as described and also additional movement imparted thereto manually by the hand lever 160. If during the inspection and manipulation of the shoe it is discovered that the upper has been pulled too far forwardly, the toe grippers can be caused to 10 release or slacken their hold upon the upper enough to let it slip backwardly and re-act under its tension. This is done by uplifting the little lever 16 and drawing upwardly upon the block 22 and the gripper stems 25. 15 This has the effect of raising the gripper stems and the gripper jaws 26 with relation to the other jaws and sleeves 30 which are held down by the connection of the sleeve with the bar 10. The incline on the back of 20 the toe gripper bar 10 holds the grippers normally forward at the time of gripping and during the initial pulling so that the stretching upper is held out of contact with the edge of the innersole to avoid lifting it. 25 As the updraw proceeds, the incline allows the grippers to move inwardly for wrapping the upper over the edge of the shoe bottom so that the grippers may reach a position substantially like that shown in Fig. 10 when 30 the machine stops. The side grippers have, for the same purpose, inclines arranged similar to that on the toe gripper bar.

When the upper has been properly adjusted and the shoe is ready for lasting, the operator depresses the latch 67 which allows the spring 66 to force forwardly into contact with the shoe the upper clamping plates or jaws 70. These plates, by reason of their mountings, adjust themselves readily to the 45 contour and the lateral position of the toe end of the last. The operator positions them vertically with relation to the plane of the bottom of the last so that said jaws clamp the upper against the edge of the 50 innersole. This adjustment of the clamping jaws also effects vertical adjustment of the lasting plates, which, like the jaws, are carried on the plate 62. This insures that the lasting plates, when they are automatically 55 operating, will come over the last bottom in the correct plane for wiping the upper firmly into lasted position. When the clamping jaws have been caused to hold the upper, the toe grippers may be released and 60 the machine is then re-started. During this automatic movement the lasting plates 80 are swung about their pivots 86 by the advance of the tack arm 60 carrying the rolls 90, and are caused to wipe or fold the upper 65 forwardly from the corners of the last cov-

ered by them, see Fig. 12, in advance of the forward wiping or folding of the upper at the toe end by the tack block 92 which, being mounted in a higher plane than the plates 80, tends to lay the upper from the 70 toe end over that wiped in from the corners.

The wipers hold the upper while the toe tacks t, t', t'' , are inserted from the tack block 92. The other tacks are inserted at the same time from the two side tackers. 75 As the drivers of the toe tacker enter the driver passages in the tack block they swing the tack block forwardly thus giving it a downward movement in the direction to force the upper against the shoulder of the 80 innersole and the tacks are preferably driven into the angle between the shoulder and feather of the innersole to obtain the best effect in holding the upper in readiness for sewing of the shoulder. 85

It will of course be understood that the usual side clamps of this machine serve to uphold the shoe during the tack driving operation. When the tacks have been inserted, the parts of the machine resume their normal positions, the latch 67 having automatically reengaged the plate 62 when the tack arm is in its advanced position, and the shoe is released in substantially the condition shown in Fig. 2. This figure represents a small turn shoe which is in readiness to be presented next to the usual welt and turn sewing machine for the permanent attachment of the upper to the sole. The inclined shoulders 42 reguide the side grippers edgewise to normal position and also the toe grippers, if the connection between said grippers shown in Fig. 3 is employed. The rear portion of the plate 62 may be inclined with relation to the front portion as 105 shown in Fig. 1, so that when the plate and the lasting devices are advanced to the shoe as shown in dotted lines, Fig. 10, they will be lifted slightly. They will then be further raised as the arm 60 advances to actuate the lasting plates. This will cause the plates to act more effectively in overwiping the upper because of their being raised automatically as they are advanced. It should also be understood that the last depressor 110 41 may advantageously stand normally at a height which will allow a shoe to be presented with its heel end high up in the machine to facilitate seizing of short uppers by the side grippers, or by the rear pair of 115 a plurality of pairs of side grippers if they are used. In the operation of the machine the depressor will automatically rock the heel end of the last downwardly to its normal relation to the other instrumentalities 120 of the machine.

The preferred use of the machine has been set forth but it should be understood that thereby no limitations are intended. For example it is within this invention to 13

- operate the toe lasting mechanism entirely by the power mechanism, allowing the latch 67 to retain the parts in the relation shown in Fig. 10 until the toe tacker mechanism 5 advances and the abutment 82 strikes the shoe and the clamping jaws 70 take up their positions about the toe automatically, whereupon the continued advance of the tack block will swing lasting plates 80 and lay 10 the upper into position to be tacked. It is found in practice, however, that more reliable and otherwise far more satisfactory preparation of the shoes for the sewing operation can be done when that feature of 15 this invention is made use of which provides for the described manual positioning of the jaws 70 and of the lasting plates 80 in accordance with the needs of the individual shoe and the judgment and skill of the workman.
- Having explained the nature of this invention and described a preferred construction embodying the same, I claim as new and desire to secure by Letters Patent of the 20 United States:—
1. In a pulling-over machine, means to engage and pull the upper at the end and opposite sides of the forward portion of the shoe, and means for moving the heel portion 25 of the last downwardly relatively to the toe portion.
  2. In a pulling-over machine, means to engage the upper at the end and opposite sides of the forward portion of the shoe, 30 means to actuate the gripping means to pull the upper, and means capable of operation to depress the rear part of the last relatively to the toe end whereby to increase the tension on the upper held by the side gripping means.
  3. In a pulling-over machine, means to engage and pull the upper at the end and opposite sides of the forward portion of the shoe, a last bottom rest arranged to engage 35 the forward portion of the last to resist the pull of the gripping means, and independently movable means to depress the rear portion of the last.
  4. In a pulling-over machine, means to engage and pull the upper at the end and opposite sides of the forward portion of the shoe, and shoe bottom engaging means including a member which is movable to rock the last about an axis located approximately at the toe end.
  5. In a pulling-over machine, means to engage and pull the upper at the end and opposite sides of the forward portion of the shoe, and shoe bottom engaging means 45 including members which are movable relatively to one another to move the last angularly through a greater distance at the heel than at the toe end.
  6. In a pulling-over machine, means to engage and pull the upper at the end and
- opposite sides of the forward portion of the shoe, a shoe bottom rest, and means additional to said rest by which to impart a differential movement to portions of the last adjacent to different portions of the gripping means. 70
7. In a pulling-over machine, a toe gripper, side grippers, means to actuate the grippers to pull an upper, a last bottom rest, and means under control of the operator to 75 move the last for increasing the tension upon the portion of upper engaged by the side grippers relatively to that engaged by the toe grippers.
  8. In a pulling-over machine, a toe gripper, side grippers, means to actuate the grippers to pull an upper, a last bottom rest, and means which can be rendered automatically operative or inoperative and can also be manually actuated to depress the last. 80
  9. In a pulling-over machine, a toe gripper, side grippers, means to actuate the grippers to pull an upper, a rest to engage the toe end of the last to resist displacement of the last by the pulling means, and means 90 engaging the last in the rear of the toe rest to move the last angularly relatively to the toe rest.
  10. A pulling-over machine, having in combination, grippers to pull an upper, and means capable of manual operation for depressing the last angularly into the pulled upper. 95
  11. A pulling-over machine, having in combination, grippers to pull an upper, and means for manually depressing the last into the pulled upper arranged to depress the heel portion of the last more than the forward portion. 100
  12. A pulling-over machine, having in combination, grippers for engaging the upper at opposite sides of the shoe, means for spreading and contracting said grippers together, and means for independently spreading and contracting said side grippers. 105
  13. A pulling-over machine, having in combination, grippers for engaging the upper at opposite sides of the shoe, means for spreading and contracting said grippers together, and means for separately positioning the spreading mechanism connected with each gripper independently. 115
  14. A pulling-over machine, having in combination, grippers for engaging the upper at opposite sides of the shoe, means for spreading and contracting said grippers together, said spreading mechanism including levers cooperating with each side gripper, and means for independently adjusting the levers. 120
  15. A machine for pulling-over and lasting turn shoes, having in combination, grippers, positioning and actuating mechanism therefor arranged to cause them to stretch 125

the upper about the last out of contact with the overhanging edge of the sole at the end and sides of the forward portion of the last and then wrap the upper inwardly over the edge of the sole during the latter part of the stretching movement, and means to last the forward portion of the pulled-over shoe.

16. A machine for pulling-over and lasting turn shoes, having in combination, grippers, positioning and actuating mechanism therefor arranged to cause them to stretch the upper about the last out of contact with the overhanging edge of the sole and then wrap the upper inwardly over the edge of the sole during the latter part of the stretching movement, wipers mounted to permit them to be manually positioned with relation to the sole, and automatic means for actuating the wipers to force the upper into lasted position upon the sole.

17. A machine for pulling-over and lasting turn shoes, having in combination, grippers, positioning and actuating mechanism therefor arranged to cause them to stretch the upper about the last out of contact with the overhanging edge of the sole and then wrap the upper inwardly over the edge of the sole during the latter part of the stretching movement, wipers, means to clamp the upper against the edge of the sole and guide the wipers relatively to the plane of the sole, and means for automatically actuating the wipers.

18. A pulling-over and lasting machine, having in combination, end lasting wipers adapted to act upon opposite sides of a shoe simultaneously, and mounted to be manually positioned in advance of their actuation, means for securing the upper in lasted position, and automatic means for operating said wipers and securing means.

19. A pulling-over and lasting machine, having in combination, end lasting wipers adapted to act upon opposite sides of a shoe simultaneously, jaws to clamp the upper against the side of the last adjacent to the plane of the shoe bottom preliminary to the overwiping operation, means for securing the upper in lasted position, and automatic means for operating said wipers and securing means.

20. A pulling-over and lasting machine, having in combination, end lasting wipers adapted to act upon opposite sides of a shoe simultaneously, jaws associated with said wipers to be positioned relatively to the plane of the shoe bottom to clamp the upper against the side face of the shoe and to guide the lasting wipers relatively to that plane, means for inserting a plurality of tacks to secure the upper in lasted position, and automatic operating mechanism for said wipers and securing means.

21. A pulling-over and lasting machine, having in combination, pulling-over means,

including automatically operating pulling devices, and lasting devices operatively connected with the pulling devices to wipe over the last bottom a continuous section of upper which has been stretched by a pulling means and extends from one side of the last around the toe to the other side, said machine having provision for permitting adjustment of the lasting devices relatively to the plane of the shoe bottom preparatory to their actuation.

22. A pulling-over and lasting machine, having in combination, pulling-over means, including automatically operating pulling devices, and lasting devices operatively connected with the pulling devices to wipe over the last bottom a continuous section of upper which has been stretched by the pulling means and extends from one side of the last around the toe to the other side, and arranged to be adjusted relatively to the plane of the shoe bottom preparatory to their lasting operation.

23. A pulling-over and lasting machine, having in combination, pulling-over means including automatically operating pulling devices, and lasting devices operatively connected with the pulling devices to wipe over the last bottom a continuous section of upper which has been stretched by the pulling means and extends from one side of the last around the toe to the other side, and arranged to be adjusted relatively to the plane of the shoe bottom preparatory to their lasting operation, and means for securing the upper in lasted position.

24. A pulling-over and lasting machine, having in combination, pulling-over means including automatically operating pulling devices, lasting devices, and manually positioned jaws to clamp the upper against the side faces of the last and guide the automatically actuated lasting devices relatively to the plane of the shoe bottom.

25. A pulling-over and lasting machine, having in combination, pulling-over grippers formed in sections and arranged to engage a continuous section of upper extending from one side around the toe to the other side of the last, means for actuating the grippers and last relatively to pull the upper, and automatically operated wipers for forcing the upper into lasted position about the toe portion of the last.

26. A pulling-over and lasting machine, having in combination, means for pulling and holding under tension a continuous section of upper extending about the toe of a shoe, means for clamping the upper about the toe portion of the shoe while it is held under tension, and power operated means for lasting and fastening the toe portion of the shoe.

27. A pulling-over and lasting machine, having in combination, means for pulling

over a shoe, and automatically operated means for lasting the forward portion of the shoe, said lasting means being movably supported for adjustment to permit manual 5 positioning thereof relatively to the plane of the shoe bottom preparatory to their automatic actuation.

28. A pulling-over and lasting machine, having in combination, a plurality of pairs 10 of jaws arranged edge to edge in close proximity to engage and hold under tension a continuous section of upper extending about the toe of the shoe, means arranged for movement by the operator after each shoe has been 15 pulled to position it properly relatively to the plane of the shoe bottom for clamping the upper against the side faces of the toe portion of the last, and automatically operated means for lasting the entire forward portion of the shoe.

29. A pulling-over machine, having in combination, sectional grippers to engage a continuous section of upper extending around the toe end of a last, means for actuating the grippers and last relatively to pull the upper, means for relatively actuating said grippers and last relatively to adjust the upper about the last, and means 25 for overworking the toe portion of the upper into lasted position.

30. A pulling-over and lasting machine, having in combination, pulling-over means constructed and arranged to permit adjustment of the upper longitudinally about the 35 toe portion of the shoe, and automatically operated means for lasting the entire toe portion of the upper.

31. A pulling-over and lasting machine, having in combination, pulling-over means 40 arranged to effect adjustment of the entire toe portion of the upper edgewise around the toe portion of the last, means for forcing said portion of the upper into lasted position, and means for fastening the upper.

45 32. A pulling-over machine having, in combination, means to pull an upper and hold it under tension about the toe portion of a last, means to last the toe portion of the shoe, and power operating mechanism for the pulling means and the lasting means, 50 said machine being organized to permit adjustment of the lasting means relatively to the pulled upper held under tension and for actuation of the lasting means at the will of the operator following such adjustment.

33. A pulling-over and lasting machine, having in combination, automatically operated means to pull over a shoe and constructed and arranged to cause a rest in 60 the machine's operation while the upper is held under tension, lasting means, said machine having provision for relative positioning movement of the shoe and the lasting means vertically to bring the plane of action of the lasting means and the plane

of the shoe bottom together, and means to fasten the upper in lasted position about the forward portion of the shoe.

34. A pulling-over and lasting machine, having in combination, means to pull over 70 a shoe, and lasting means comprising relatively movable clamping jaws arranged for initial engagement with the pulled upper immediately below the plane of the shoe bottom, and lasting plates arranged for subsequent overwiping engagement with the upper immediately above the plane of the shoe bottom.

35. A pulling-over and lasting machine, having in combination, means to pull over a 80 shoe, and lasting means comprising pivotally connected clamping jaws formed and arranged to embrace the toe portion of the shoe immediately below the plane of the shoe bottom, and lasting plates arranged for subsequent overwiping engagement with the upper immediately above the plane of the shoe bottom.

36. A pulling-over and lasting machine, having in combination, means to pull over 90 a shoe, and lasting means comprising clamping jaws arranged for initial engagement with the pulled upper immediately below the plane of the shoe bottom, and lasting plates which include corner wipers, a toe 95 end wiper, and means for actuating the corner wipers in advance of the end wiper.

37. A pulling-over and lasting machine, having in combination, means to pull over a shoe, and lasting means comprising clamping jaws arranged for initial engagement with the pulled upper immediately below the plane of the shoe bottom, lasting plates which include corner wipers, a toe end wiper mounted over the corner wipers, and operating means arranged to cause the corner wipers to act ahead of the end wiper.

38. A pulling-over and lasting machine, having in combination, means to pull over 100 a shoe, and lasting means comprising the pivotally connected, endwise movable upper clamping jaws 70, and lasting plates.

39. A pulling-over and lasting machine, having in combination, means to pull over 110 a shoe, and lasting means comprising pivotally connected, independently spring pressed clamping jaws and lasting plates arranged relatively for the purpose described.

40. A pulling-over and lasting machine, having in combination, means to pull over 120 a shoe, and lasting means comprising the clamping jaws 70, the yielding actuating means 73, 74 therefor, and the spring pressed plunger 76 arranged to apply pressure through the jaws to the middle portion of the toe.

41. A pulling-over and lasting machine, having in combination, means to pull over a 130 shoe and lasting means comprising clamping

jaws which can be manually positioned in holding engagement with the pulled upper, and automatically actuated lasting plates.

42. A pulling-over and lasting machine, having in combination, means to pull over a shoe, and lasting means which can be manually positioned relatively to the shoe and automatically actuating mechanism therefor.

43. A pulling-over and lasting machine, 10 having in combination, means to pull over a shoe, and lasting means which can be manually positioned relatively to the plane of the bottom of that portion of the shoe upon which they are to operate, and means for 15 automatically actuating said devices to do their work.

44. A pulling-over and lasting machine, having in combination, means to pull over a shoe, and lasting means which can be 20 manually positioned relatively to the plane of the bottom of that portion of the shoe upon which they are to operate, and comprising jaws to clamp the upper against the side of the shoe, and power driven lasting 25 plates.

45. A pulling-over and lasting machine, having in combination, pulling-over means, lasting plates, power driven means therefor arranged to bring the machine to rest between the operations of said pulling-over 30 means and lasting plates, and upper clamping jaws arranged to be manually positioned during said period of rest to hold the pulled upper for the lasting plates.

46. A pulling-over and lasting machine, having, in combination, pulling-over means, lasting plates, and power driven means therefor arranged to bring the machine to rest between the operations of said pulling-over 40 means and lasting plates, said lasting plates being arranged for manual positioning movement relatively to the plane of the bottom of the last which is in the machine to adapt them for the shoe during said period 45 of rest.

47. A pulling-over and lasting machine, having in combination, pulling-over means, lasting means, and power driven mechanism for the pulling-over means and the lasting 50 means arranged to produce a pause after the operation of the pulling-over means, said lasting means including wiper plates mounted to be moved manually from an inoperative position to a position in proximity to 55 the shoe and to be initially positioned around the shoe during said pause.

48. A pulling-over and lasting machine, having in combination, pulling-over means, lasting means, and power driven mechanism 60 for the pulling-over means arranged to produce a pause after the operation of the pulling-over means, said lasting means including upper clamping jaws arranged to be manually positioned during said pause, and 65 wiper plates.

49. A pulling-over and lasting machine, having in combination, pulling-over means, lasting means, and power driven mechanism for the pulling-over means arranged to produce a pause after the operation of the pulling-over means, said lasting means including upper clamping jaws and wiper plates arranged to be manually positioned relatively to the plane of the shoe bottom during 70 said pause.

50. A pulling-over and lasting machine, having in combination, means to pull over an upper, and means to secure it including a tack holder which is mounted to be moved forwardly by the drivers and has a driver 80 passage and a driver arranged at an angle to the direction of the driver passage to move the tack holder forwardly in the direction of the upper overdriving movement as it descends to insert the tack.

51. A pulling-over machine, having in combination, means to pull over an upper, and means to secure it including a swinging tack holder having driver passages, and a 85 driver bar, having drivers pivotally mounted thereon, and normally occupying a position at an angle to the driver passages and adapted to be turned into alignment therewith by engagement with the walls of the driver passages and to cause the tack holder 90 to force the upper in the direction of the overdriving movement.

52. A pulling-over machine, having in combination, means to pull over an upper, and means to secure it including a tack 100 holder having driver passages, a driver bar, and means for guiding the driver bar in a path at an angle to the normal direction of the driver passages, said parts being constructed and arranged for relative movement to insert tacks at an angle to the direction of the driver bar path so as to aid in forcing the upper in the direction of the overdriving movement.

53. A pulling-over and lasting machine, 110 having in combination, curved grippers formed to engage an upper at the opposite sides and toe end of a last, and means for relatively actuating the grippers and the last to pull the upper, including means for depressing 115 the heel end of the last relatively to the toe end for the purpose described.

54. A pulling-over machine, having in combination, with suitable automatic operating mechanism, shoe bottom resting means 120 comprising a member to engage the forepart of the shoe bottom and a member located in the rear thereof and operated to move the heel portion of the last downwardly with relation to the toe portion.

55. A pulling-over machine, having in combination, with suitable automatic operating mechanism, shoe bottom resting means comprising a member to engage the forepart 125 of the shoe bottom and a member located in 130

the rear thereof and adapted to be raised to permit the presentation of the shoe for a short upper to be seized and to be depressed relatively to the front member to depress the shoe angularly into its normal plane.

56. A pulling-over machine, having in combination, grippers comprising a plurality of sections arranged to engage the upper about the toe and adjacent parts of the sides of a last, and means for relatively actuating the grippers and the last to pull the upper, including means for depressing the heel end of the last relatively to the toe end.

57. A machine for working an upper over the forepart of a last having, in combination, end embracing wipers, grippers comprising two pairs of jaws separate from the wipers and formed and arranged to engage the upper at the curved portions of the toe on opposite sides of the end of the toe, means for relatively actuating the grippers and the last in a direction to tighten the upper and maintain it under tension until the wipers engage it, and automatic means for actuating the wipers to lay the upper into lasted position about the toe of the last.

58. A pulling-over machine, having in combination, sectional grippers to engage a continuous section of upper extending around the toe end of a last, means for actuating the gripper and last relatively to pull the upper, means for relatively actuating said grippers and last rotatively to adjust the upper about the last, and means for overworking the toe portion of the upper into lasted position.

59. A pulling-over machine having, in combination, means to pull an upper and hold it under tension, means to fasten the upper, lasting means to lay a continuous section of the upper extending from one side of the shoe around the toe of the shoe to the other side thereof in position to be secured by the fastening means, and power operating mechanism for the lasting and fastening means, said machine being organized to permit adjustment of the lasting means between the pulling and the fastening operations into operative relation to the plane of the bottom of the toe portion of the particular shoe being worked upon.

60. A pulling-over and lasting machine having, in combination, means for pulling and holding under tension a continuous section of upper extending about the toe of a shoe, means for clamping the upper at the edge of the bottom of the toe portion of the shoe, and automatically operated means adjustable manually prior to such operation relatively to the plane of the bottom of the shoe in the machine for lasting the entire forward portion of the shoe.

61. A pulling-over and lasting machine having, in combination, pulling-over means, lasting plates, and power driven means

therefor arranged to bring the machine to rest between the operations of said means and plates, said machine having provision for adjusting the upper on the last and for relative vertical movements of the pulled over shoe and the lasting plates to bring them into operative relation preliminary to the power operation of the wipers.

62. A pulling-over and lasting machine having, in combination, pulling-over means, lasting means, and power driven mechanism therefor arranged to produce a pause after the operation of the pulling-over means, said machine being constructed and arranged to permit movement of the shoe and the lasting means relatively in a direction lengthwise of the shoe and angularly to bring them into proximity and proper working relation after the pulling has been effected with the lasting means in a remote position to render the shoe readily observable by the workman.

63. A pulling-over and lasting machine having, in combination, upper pulling grippers, upper securing means, toe embracing wipers mounted to be manually positioned vertically relatively to the shoe after the upper has been pulled, means for operating the wipers to lay the upper into position to be fastened, and means for operating the securing means to tack the upper overlaid by the wipers.

64. A pulling-over and lasting machine having, in combination, upper pulling grippers, upper securing means, toe embracing plates mounted to be manually positioned relatively to the shoe after the upper has been pulled, means for releasing the grippers from the toe portion of the upper, and power driving means to lay the upper over the toe portion of the last and to fasten the upper.

65. A pulling-over and lasting machine having, in combination, upper pulling grippers, upper securing means, power driving mechanism therefor, said machine being organized to come to rest after the pulling operation with the toe portion of the upper held under tension, and toe embracing plates mounted to be manually positioned around the pulled upper of the toe portion of the shoe during such period of rest, said mechanism being arranged to effect the overlaying of the upper preparatory to the securing operation when the machine is restarted.

66. A pulling-over and lasting machine having, in combination, upper pulling grippers, upper securing means, power driving mechanism for the securing means, said machine being organized to hold the pulled upper under tension about the toe portion of the last, and lasting means including toe embracing wipers mounted to be manually positioned around the pulled upper of the toe portion of the shoe and to be automatically

cally operated by said mechanism to overlay the upper and hold it for the securing operation.

67. A pulling-over and lasting machine having, in combination, upper pulling grippers, upper securing means, power driving mechanism therefor, said machine being organized to come to rest after the pulling operation with the toe portion of the upper held under tension, lasting means including toe embracing clamping plates and lasting plates mounted for positioning movement to cause the clamping plates to embrace and hold the toe of the upper at the edge of the last and to locate the lasting plates at the right altitude relatively to the plane of the shoe bottom, and connections from said mechanism for operating the lasting plates to overlay the upper and the securing means to fasten it.

68. A pulling-over and lasting machine having, in combination, upper pulling grippers, upper securing means, toe lasting means, and operating mechanism all organized to hold the pulled upper under tension for inspection and to permit manual positioning of the lasting means into operative relation to the pulled upper and thereafter to cause the lasting means and the securing means to perform their operations automatically.

69. A pulling-over and lasting machine having, in combination, means for pulling and holding under tension a continuous section of upper extending around the toe of the shoe, means mounted for adjusting relative to the plane of the bottom of the pulled shoe for clamping the upper against the edge of the sole around the toe portion of the shoe, and means for working into lasted position the marginal portion of the entire forward part of the shoe that is so tensioned and clamped.

70. A pulling-over machine having, in combination, means to pull an upper and hold it under tension, means to last the toe portion of the shoe, and power operating mechanism, said machine being organized to permit adjustment of the lasting means relatively to the pulled upper held under tension and for actuation of the lasting means at the will of the operator following such adjustment.

71. A pulling-over machine having, in combination, means to pull an upper and hold it under tension, means to fasten the upper, lasting means to lay a continuous section of the upper extending from one side of the shoe around the toe of the shoe to the other side thereof in position to be secured by the fastening means, and power operating mechanism for the lasting and fastening means, said machine being organized to permit adjustment of the lasting means between the pulling and the fastening

operations into operative relation to the plane of the bottom of the toe portion of the particular shoe being worked upon.

72. A pulling-over machine having, in combination, means to pull over a shoe, lasting means comprising toe embracing plates mounted for adjustment toward the shoe and into operative relation to the plane of the bottom of the toe portion of the shoe after the upper has been pulled, and power mechanism to operate the plates to lay the upper into lasted position and hold it for a fastening operation on the upper.

73. A pulling-over machine having, in combination, means to pull over a shoe, lasting means comprising toe embracing plates mounted for adjustment toward the shoe and into operative relation to the plane of the bottom of the toe portion of the shoe after the upper has been pulled, power mechanism to operate the plates to lay the upper into lasted position, and securing mechanism arranged to operate automatically to fasten the upper while the plates hold it.

74. A pulling-over and lasting machine having, in combination, pulling-over means and lasting means including toe embracing jaws and superposed wiper plates mounted for manual positioning of the jaws around the work and of the jaws and the plates at the desired elevation relatively to the bottom of the pulled over shoe, power mechanism for operating the lasting plates, and upper securing means.

75. A pulling-over and lasting machine having, in combination, pulling-over means and lasting means including a carrier plate movable lengthwise of the shoe and also up and down and upper clamping jaws and lasting plates mounted on the plate to be positioned relatively to the shoe by such movements, and means to operate said lasting plates.

76. A pulling-over and lasting machine having, in combination, pulling-over means and lasting means and upper clamping jaws mounted and arranged to be manually adjusted and held in upper holding position during the operation of the lasting means.

77. A pulling-over and lasting machine having, in combination, pulling-over means and lasting means, and upper clamping means mounted for manual adjustment into upper holding position, means for yieldingly holding the clamping means in operative position and other means for operating the lasting means.

78. A pulling-over and lasting machine having, in combination, pulling-over means, and clamping means comprising a supporting plate, a jaw, a stem therefor slidably mounted in the jaw and a yieldingly out-pressed plunger for positioning the jaw relatively to the plate.

79. A pulling-over and lasting machine having, in combination, pulling-over means, and clamping means comprising a supporting plate, a pair of connected jaws, stems for the jaws sliding in the plate, and separate spring-pressed plungers for positioning the jaws relatively to the plate.

80. A pulling-over and lasting machine having, in combination, pulling-over means, and clamping means comprising a supporting plate, a pair of connected jaws, stems for the jaws sliding in the plate, and separate spring-pressed plungers for positioning the jaws relatively to the plate, said plungers being arranged between the stems and the connected ends of the jaws and maintaining their connected ends normally advanced relatively to their outer ends.

81. A pulling-over and lasting machine having, in combination, pulling-over means and lasting means including toe embracing wipers, a carrier plate on which the wipers

are pivoted and which is mounted for positioning movement toward and from the work, an actuator having pin and slot operating connections with the wipers and with relation to which said positioning movement of the plate takes place, and driving mechanism to cause the actuator to turn the wipers to lay the upper over the toe bottom.

82. In a pulling-over machine, grippers for engaging an upper, power operated means for moving the last into the upper, and a manually operated device adapted for manipulation while the upper is under strain for moving the last downwardly after the actuation of the power operated means.

In testimony whereof I have signed my name to this specification in the presence of two subscribing witnesses.

ORRELL ASHTON.

Corrections in Letters Patent No. 1,137,564.

It is hereby certified that in Letters Patent No. 1,137,564, granted April 27, 1915, upon the application of Orrell Ashton, of Swampscott, Massachusetts, for an improvement in "Machines for Use in the Manufacture of Boots and Shoes," errors appear in the printed specification requiring correction as follows: Page 5, line 68, for the word "limiting" read *limited*; page 10, lines 70, for the article "a" read *the*; page 14, line 36, for the word "adjusting" read *adjustment*; and that the said Letters Patent should be read with these corrections therein that the same may conform to the record of the case in the Patent Office.

Signed and sealed this 1st day of June, A. D., 1915.

[SEAL.]

J. T. NEWTON,

Acting Commissioner of Patent
